WEB UNWIND APPARATUS

Danahey Ryan, Wilmington, Del., assignor to E. I. du Pont de Nemours and Company, Wilmington, Del., a corporation of Delaware

Filed Aug. 1, 1963, Ser. No. 299,244

7 Claims. (Cl. 242—53.1)

This invention relates to web handling apparatus and, more particularly, it relates to apparatus for use in continuously unwinding web from separate spools.

During the production and handling of web-form materials it is frequently necessary or desirable to wind the unfinished web in spools or rolls prior to finally finishing or processing the web. In the manufacture of light-sensitive cine film, the film is generally wound on large spools prior to perforation, inspection, key numbering and rewinding on small spools of exact lengths. This requires a device capable of continuously unwinding the unfinished film at a high rate of speed for introduction into the finishing process. The film should be fed at a constant tension but owing to its light-sensitive nature and general fragility great care must be taken which is not possible with conventional web handling equipment. Since the device must operate in nearly complete darkness the operation should be as nearly automatic as possible with a minimum need for operator attention. Further, when a spool is exhausted the device must be capable of automatically initiating a splicing operation to a new spool with a minimum of time loss.

It has been found that these and other important objects and advantages are accomplished in accordance with this invention which is particularly pointed out in the appended claims and is illustrated, in its preferred embodiments, in the accompanying drawings wherein:

FIG. 1 shows an elevation view of a general arrangement of the apparatus of the invention;

FIG. 2 shows a partial plan view taken generally along line 2—2 of FIG. 1;

FIG. 3 is an enlarged sectional view of the turret supporting shaft assembly taken generally along line 3—3 of FIG. 2;

FIG. 4 is a sectional view taken along line 4—4 of FIG. 3;

FIG. 5 is a partial view partly in section of the unwind spindle assemblies generally taken along line 5—5 of FIG. 7;

FIG. 6 is an enlarged partial sectional view of the spindle assembly 11a of FIG. 5;

FIG. 6A is an elevation view of the knob 59 shown in FIG. 6;

FIG. 6B is an enlarged fragmentary view of the end of the element 56 shown in FIG. 6;

FIG. 7 is an enlarged elevation view of the turret shown in FIG. 1 with the follower arm assemblies shown in detail;

FIG. 8 is a sectional view taken along line 8—8 of FIG. 7 showing the details of the follower arm assembly;

FIG. 9 is an enlarged partial view of the turret and related elements in the area adjacent the splicing mechanism;

FIG. 10 is an enlarged plan view of the camming surface 86 and related roll 85;

FIG. 11 is a partial plan view taken along line 11—11 of FIG. 9.

Referring to FIGS. 1, 2 and 3, the apparatus of this invention comprises essentially a circular, rotatable turret plate 10 on which are mounted two unwind spindle assemblies 11a and 11b at opposite ends of the turret diameter. Each spindle assembly is complemented by an unwind follower arm 12 and dancer roll assembly 13 and

2

their associated elements, respectively. For purposes of simplifying the discussion, only spindle assembly 11a and its complementary apparatus are described in detail; however, it is to be understood that the spindle assembly 11b and its complements are structurally and functionally identical. As can be seen in FIG. 1 the web 78 emerges from the apparatus in the direction of the arrow; suitable means (not shown) are provided to drive the web in this direction, e.g., positively driven wind-up rolls or the like.

As shown in the drawings, the turret assembly comprises a circular plate 10 mounted at its axial center to a rotatable, hollow hub 14 which, in turn, is rotatably supported on a pair of spaced bearings 15a and 15b in a box-like housing 16. The housing 16 is rigidly secured to the main machine frame designated generally by numeral 17.

Referring more particularly to FIG. 3, the hub 14 is shown to extend beyond the bearings 15a and 15b at either end. One end is affixed to the plate 10 and the other end is provided with a locking collar 18 that has two open slots 19a and 19b spaced 180° apart and a pulley 20. Both the locking collar 18 and the pulley 20 are firmly keyed to the hub 14 for rotation therewith. Between the bearings 15a and 15b inside the housing 16, a commercial slip ring assembly 21 (manufactured by the Breeze Corp.) is mounted on the hub 14 for rotation therewith.

The ring assembly 21 consists of a series of spaced electrically insulated disks 22 that have annular-shaped conductive rings 23 (see FIG. 4) on both faces. Four of the rings 23 are split into 180° arc lengths while the remaining fourteen rings have full 360° lengths.

In FIG. 4, each ring 23 is contacted by a brush 24 which is mounted in a brush holder 25 affixed to the housing 16. The brush holder 25 carries a brush 24 which is electrically connected to one end of a power supply (not shown) which forms one-half of the electrical circuitry. The conductors forming the other half of this circuitry (not shown) are attached directly to the rings 23 inside the hub 14. The conductors are combined into a cable and emerge through an opening 26 in the hub 14 whereupon they connect to the various switch and load devices mounted on the turret assembly (not shown).

Shown inside the hollow hub 14 is a spindle drive shaft 27 rotatably mounted concentric with the hub 14 axis. Pulleys 28 and 29 are fixed at the turret end of the shaft 27 and by means of timing belts 30 and 31, respectively, engage pulleys 49 on the spindle assemblies 11a and 11b as shown in FIG. 5. The other end of the shaft 27 extends beyond the end of hub 14 and, as shown in FIG. 3, carries a pulley 32. The pulley 32 engages a timing belt 33 which engages a similar pulley 34 fixed to the shaft of a constant torque motor 35, shown in FIG. 2, which is securely mounted to the machine frame 17.

In FIG. 2, adjacent to the motor 35 and attached to the machine frame 17, is a speed reducer motor 36 to which is attached a pulley 37; by means of a timing belt 38, the motor 36 is operatively connected to the pulley 20 on the hub 14 thus providing rotative power to the turret plate to be indexed 180°. Referring to FIG. 3, the hub 14 may be locked in place by means of a dog 39 which enters either of the slots 19a or 19b; the dog 39 is slidably journaled in a bracket 40 which is mounted to the housing 16. The dog 39 abuts the spring 41 which functions to urge the tapered end of the dog 39 into engagement with either slot. The other end of the dog 39 is coupled by a pin 42 to the plunger 43 of a conventional solenoid (not shown) which, upon being energized, functions to withdraw the dog 39 from engagement with the slot in the collar 18.

Referring now to FIGS. 5 and 6, the spindle assemblies 11a and 11b are described in detail below. As previously

mentioned for simplifying the discussion, only spindle assembly 11a is discussed. The spindle 11a is an assemblage of rotating components contained in a hollow housing 44 mounted to the turret plate 10. Within the housing 44 is a hollow shaft 45 rotatably supported on a pair of spaced frictionless bearings 45a and 45b and communicates on either end through the turret plate 10. The portion of the shaft 45 on the front side of plate 10 is enlarged in diameter and has an open cavity. The other end of the shaft 45, passing through to the back side of the plate 10, is coupled to a shaft 45 upon which is mounted a commercial, electrical clutch-brake mechanism 47 (manufactured by the Simplatrol Corporation) housed in an extension 48 of the housing 44. A pulley 49 is fixed to a rotating coil of the clutch portion of the clutch-brake 47 and is engaged by the belt 30 to the pulley 28 shown in FIG. 3. When the clutch coil (not shown) of the clutch-brake 47 is energized, the clutch is thus engaged and the brake coil (not shown) is de-energized and the brake is released; thus, the motor 35 is coupled to the shaft 45 and exerts a "reverse" torque on the shaft 45; i.e., the direction of the motor torque is such as to resist the force of the unwind drive means which causes the withdrawal of web 78 from a core 63 secured to the shaft 45. If the web is not being withdrawn, the shaft 45 will rotate in the "reverse" direction until downstream web slack is taken up and the shaft 45, thereafter, will stand still until the web is moved by some agency other than the motor 35. If the clutch coil is de-energized and the brake coil is energized, the pulley 49 and part of the clutch-brake 47 will rotate in the "reverse" direction under the urging of the motor 35; however, the shaft 45 will not rotate since it is restrained by the brake.

Interposed between the bearings 45a and 45b is a non-conducting sleeve 50 affixed to the shaft 45 for rotation therewith. Metal bands 51 and 52 are embedded about the circumference of the sleeve 50 and are in rubbing contact with a pair of stationary brushes 53 and 54. The brushes 53 and 54 are juxtaposed in recesses in the housing 44 and are connected by insulated conductors (partially shown) to appropriate rings 23 of the slip ring assembly 21. At their inner end, the metal bands 51 and 52 are connected by insulated conductors to an indicator lamp 55 shown threadedly attached at the base of the enlarged portion of the shaft 45.

Concentric with the lamp 55 is a hollow adaptor 56 threadedly attached within a cavity in the end of shaft 45 thus forming an extension of the latter. As shown in FIG. 6B the external end of the adaptor 56 is modified by a cam contour having flat surfaces 57a and 57b separated by protruding lugs. Engaging these surfaces is the split tang 58 portion (see FIG. 6A) of a hollow knob 59. The knob 59, in turn, is coupled to a flanged sleeve 60 which is slidably telescoped inside the hollow adaptor 56. A spring 61 which abuts the flange of the sleeve 60 and an internal shoulder in the adaptor 56 urges the tang 58 against the cam surfaces. A spring 62, anchored at one end to the knob 59 and at the other end to the adaptor 56, is interposed between the adaptor 56 and functions as a radially expandable means for frictionally chucking a spool or core 63. A series of holes (not shown) spaced circumferentially on the hollow adaptor 56 provide rough adjustment of the spring 62 diameter. The diameter is adjusted to be slightly less than the inside diameter of the core 63. This facilitates mounting and removal of a core 63 from the spindle assembly. The final incremental increase in the spring 62 diameter for frictionally engaging the core 63 is accomplished by manually rotating the knob 59. The cam surfaces 57a and 57b limit the angular rotation of the knob 59 and function to maintain the spring 62 in the contracted condition during loading or unloading, the spring 62 being wound so as to expand when tang 58 rests against cam surface 57b.

Referring to FIGS. 7 and 8, a follower arm assembly

12 on the face of the turret 10 is pivotally supported on a shaft 64. At its outer end, the follower arm 65 carries a roller 66 which is covered with an elastomeric material which rides in contact with the outer periphery of a film roll 90b which is being unwound. One end of the pivot shaft 64 is attached to the arm 65 while the other end, on the back side of the plate 10, is attached a radially adjustable counterweight 68 which shares the hub with one link 69 of a 4-bar linkage system. The link 70 at the other end of the linkage system is gear-connected to the adjustable portion of a conventional variable auto-transformer 71 which functions to control voltage in response to movement of the arm 65 and by that means, the torque output of the motor 35. In this manner the unwinding force exerted by the unwind drive means (not shown) is resisted to a varying amount depending upon the movement of arm 65. In carrying out this function, the follower arm assembly 12 thus serves to monitor film roll diameter as described below.

Referring to FIGS. 7, 9-11, the dancer roll assembly 13 consists of an arm 72 which is keyed to a shaft 73 which shaft is suitably journaled in the turret 10. On the back side of the turret 10, the shaft 73 is keyed to a cam 74 that operatively engages cam follower 75 of a microswitch 76. On the extremity of the arm 72, a roller 77 is rotatably journaled to contact the web 78 during operation. During a normal unwinding operation, the roller 77 is supported by a loop in the web as shown in FIG. 9; however, if the end of a film roll is reached or if the web 78 breaks for any reason (causing a loss in tension), then the arm 72 and dancer roll 77 will drop to the position 72' shown in phantom lines and the microswitch 76 will be actuated by the cam 74 and cam follower 75. This action results in other effects which are described below.

Referring to FIGS. 9, 10 and 11, a web guiding roll 79 is provided which is rotatably mounted in suitable anti-friction bearings 150 on the main machine frame immediately to the right of the turret 10. The roll 79 and its mounting are shown in FIG. 11 where it may be seen that the back end of the shaft 152 carries a pair of anti-friction bearings 151 upon which is mounted a pulley 153. The pulley 153 is engaged by a toothed belt 83 which also passes around adjustable pulley 85 (which is an idler), and pulley 154 on shaft 155 from which latter pulley 154 the belt 83 receives its power. In FIG. 11 it may also be seen that the rear part 79a of the roll 79 has a larger diameter than the front part which latter is the portion the web 78 passes over. Similarly, the dancer roll 77 has a larger diameter section 77a to the rear of the section that engages the web. These enlarged sections 77a and 79a on the rolls are intended to come into contact with each other during a part of the time when the turret 10 is rotated, i.e., indexed from one position to another. When this occurs the dancer roll assembly is substantially horizontal and the roll 77 is accelerated by the rolling contact between roll sections 77a and 79a. The bearings 151 were identified (above) as being of the anti-friction type; however, despite the fact that these bearings roll on balls, some small amount of friction is present. Therefore, when the pulley 153 is rotated (by the belt 83), the outer races of the bearings 151 will be rotated and then, by friction, the inner races will be rotated. Thus, power is transmitted to the roll 79 which is rotated at the desired web speed; the advantage of this type construction is that, if the web is subjected to an acceleration from some other source, the roll 79 is capable of following the change in web speed; however, the torque exerted on the roll by the web will be slight and, therefore, the possibility of damage to the web surface (e.g., due to relative slippage) is considerably decreased.

Roller 80 is mounted on shaft 81 which is journaled in antifriction bearings in the turret 10; each roll 80 is associated with a dancer roll assembly 13 and is situated in close proximity to roll 77. In back of the turret, the

shaft 81 is provided with a cylindrical disc 82 which, when the turret 10 is indexed, will make rolling frictional contact with the outer periphery of the running belt 83 in the generally vertical portion of the belt 83 extending from pulley 85 to pulley 153, the disc 82, the shaft 81, and the roll 80 being accelerated thereby.

Referring to FIGS. 9, 10 and 11, a wedge-shaped cam 86 is rigidly attached to the main machine frame 17 immediately to the right of the turret 10 and above the roll 79; this fixed cam 86 serves to support the dancer roll assembly 13 when the turret 10 is indexing. The cam follower 87 behind roll 77 engages the inclined surface of the cam 86 during only a part of the time that the turret 10 is in motion; during this time the cam follower 87 proceeds to run down the incline on the cam 86 until eventually it drops off; at this stage the large portion 77a of roll 77 comes in contact with the large portion 79a of roll 79. Further rotation of the turret 10 allows the roll 77 to pass between rolls 79 and 84 to form the loop in the web 78. This is further discussed below.

Referring to FIG. 11, roll 84 is mounted on antifriction bearings 156 which, in turn, are mounted on the shaft 155; this shaft 155 is power driven by pulley 157 by belt 158. The roll 84 is rotated at web speed by virtue of bearing friction as described above for roll 79 with the same advantage.

Referring to FIG. 9, rolls 84 and 83 are associated with a web splicing device, known as a wiper-roll splicer, which is fully described in my copending U.S. application, Serial No. 167,583, filed January 22, 1962. Because of its gentle acceleration characteristics, this web splicer together with the web unwinding device being described herein forms a preferred embodiment though it is recognized that other web splicing devices known in the art may be used. In general, it should be realized that the nature of the operations being carried out downstream of the unwind device and the splicer is such that it is permissible to stop operations momentarily, upon the exhaustion of a supply roll, to allow time for splicing the expiring or trailing end of one web roll to the leading end of a new roll. Thus, an "on-the-fly" type of web splicer is not required here; in general, any type splicer which is adapted to join the ends of two non-moving webs could be used. For use with the invention described herein, the wiper roll splicer is furnished with a slack takeup roll 159 as shown in FIG. 9 which is adapted to be driven in synchronism, at a 1-to-1 ratio, with the wiper roll 97 of the splicer by a means not shown. The slack take-up roll 159 turns clockwise as the wiper roll 97 and the web move to the left thus, the roll 159 helps to urge the web to the left.

Referring particularly to FIG. 1, in operation, assume that a web 78 is being unwound from the lower of the two spindles, denoted by 11b. The web 78 runs from the bottom of the film roll 90b, up underneath roll 80, over roll 79, underneath the roll 77 of the dancer roll assembly 13, above roll 84 around roll 88 and thence down to rolls 91 and 92 and on into some device (not shown) in which the web is being consumed at a substantially constant rate of, for example, about 1,000 ft./min. As previously stated, the web will be positively driven by some unwind drive means (not shown) which will exert the principal unwind force on the web 78. Many suitable means for effecting this force will be apparent to one skilled in the art. The web 78 is unwound from the spindle assembly 11b while the spindle assembly 11a at the upper portion of the turret 10 is inactive and is held in a braked condition by the clutch-break mechanism 47.

A new supply roll 90a is now mounted on the upper spindle assembly 11a and prepared for automatic splicing in the following manner. Assuming that the core 63 from some previous supply roll is still on the spindle, the operator manually removes it by pulling the knob 59 outward and rotating it clockwise. The tang 58 dis-

engages from the cam surfaces 57b and enters cam surface 57a thus causing the outside diameter of the torsion spring 62 to decrease, releasing the core 63.

If the web 78 is unexposed cine film it must be processed in a darkened environment; since the supply roll 90a is about twenty-four inches in diameter, the indicator lamp 55 in the center of the hub provides a convenient means for assisting the operator in locating the spindle. Once the roll 90a is mounted, the operator reverses the knob 59 sequence causing the spring 62 to chuck or grip the core of the new supply roll.

The leading end of the new roll 90a is manually withdrawn from the roll and the new web 78' is passed over web guide roll 95, under roll 96, under the slack take-up roll 159 and thence to the top of roll 97 where it is manually secured by means of a piece of pressure sensitive tape. The manner in which the new web end 78' is secured to the roll 97 is fully described in U.S. application, Serial No. 167,583 (supra) and will not be repeated here. At this stage the new roll 90a and the new web 78' are left in a static condition pending the exhaustion of the film roll 90b.

As the web 78 is unwound, the diameter of the roll 90b decreases and this alters the load requirements on the torque motor 35. To compensate for this change so that constant tension of about one pound is maintained on the web 78, the follower arm assembly 12 monitors the nominal diameter of the roll 90b. As the diameter decreases, the arm assembly 12 pivots and shifts the 4-bar linkage (69 and 70) which, in turn, change the voltage setting of the auto-transformer 71 that controls the motor 35.

When the tail end of the web 78 leaves the core 63 on the spindle assembly 11b, web tension is lost and the dancer roll assembly 13 then drops downward. This rotates the cam 74 which actuates switch 76 thus causing the machine to stop which causes the clutch-brake on lower spindle assembly 11b to be actuated, i.e., to engage the brake and disengage the clutch while simultaneously activating the splicer. The knife 160 on the splicer then severs the web 78 between the rolls 84 and 88. At the instant of completion of this cut, the solenoid 43 is energized and the dog 39 is retracted which unlocks the turret 10; simultaneously, the speed reducer motor 36 energizes to cause the turret 10 to begin to index clockwise for 180° and the clutch-brake on upper spindle assembly 11a is energized to engage the clutch and disengage the brake. The waste end of the web 78 which, at this time, is trapped between the roll 80 and the roll 77 is thus pulled away from the left part of the splicer by the rotation of the turret. At the same time the splicing mechanism is actuated as described in U.S. application, Serial No. 167,583 (supra) thus causing the web ends to be spliced together. In the course of the splice cycle web slack is created which is taken up by "reverse" action of the spindle motor 35. When the splicing sequence is complete, the unwind drive means of the machine to which the web is being supplied (not shown) starts to withdraw the spliced web 78 from the unwind and accelerates the web to full speed during which time the turret plate 10 continues to index. As the turret approaches the 180° position, dancer roll assembly 13 and roll 80 come into proximity to roll 79. Roll 80 passes to the left of roll 79 while the dancer arm 72 is restrained by the stationary cam 86 so that it eventually passes to the right of roll 79. At the instant before these two elements pass roll 79 behind the machine, roll 80 is brought up to web speed by belt 83 and roll 77a is likewise brought up to web speed by contact with roll 79a. At this point, the web passes from the top of roll 79 to the top of roll 84 without being deflected. As the indexing of the turret continues beyond this point, the web 78 is deflected downward by roll 80 and as roll 77 (on dancer roll assembly 13) is released by the cam 86 and then by the roll 79 and passes between rolls 79 and 84, the web 78 is automatically threaded beneath the roll 77 to the position shown in FIG. 1. Spin-

dle 11b is now in the upper position of the turret plate 10 and the empty core 63 can be manually removed by the operator and a new supply roll put in position and prepared for splicing in the same manner previously described. When the turret 10 reaches the 180° position, the dog 39 again locks it in position.

The unwinding apparatus of this invention is highly advantageous for handling light-sensitive cine film, particularly since such handle must occur in the virtual absence of light. Further, the automatic indexing of the turret in such a manner as to have the film from the fresh spool automatically positioned, i.e., in a loop beneath the second dancer roll, is a distinct advantage.

What is claimed is:

1. In a device for unwinding web from spools by the action of an unwind driving force the combination comprising a turret, a pair of rotatable spindles on said turret each adapted to receive a spool, unwind torque means for resisting the rotation of each spindle caused by said driving force, sensing means for sensing the decreasing diameter of web on a spool, control means responsive to said sensing means for reducing the resisting torque of said unwind torque means thereby maintaining constant tension in said web as it is being unwound, means for detecting the exhaustion of the web from a spent spool, said turret having indexing means for positioning a fresh spool into position for being unwound upon being actuated by said detecting means, and means for splicing of the trailing end of said web to the lead end of the web from the fresh spool when actuated by said detecting means.

2. In a device for unwinding web from spools by the action of an unwind driving force the combination comprising a turret, a rotatable spindle on said turret adapted to receive a web containing spool, unwind torque means for resisting rotation of said spindle caused by said driving force, sensing means for sensing the decrease in diameter of web being unwound from said spool, control means responsive to said sensing means for reducing the resisting torque of said unwind torque means thereby maintaining a constant tension in said web as it is being unwound, turret indexing means for moving a fresh spool into position for unwinding and means for detecting the exhaustion of web from said spool being unwound thereby initiating said indexing means.

3. In a device for unwinding web from spools by the action of an unwind driving force the combination comprising a turret, a pair of rotatable spindles on said turret adapted to receive first and second spools, a dancer roll supportable by the web being unwound from said first spool, actuating means in association with said dancer roll which is activatable by said dancer roll upon the discontinuance of said supporting web and turret indexing means for rotating said turret and thereby positioning said second spool into a position for being unwound, said indexing means being activatable by said actuating means.

4. A device as defined in claim 3 including means for splicing the trailing end of said web unwound from said

first spool to the leading end of the web to be unwound from said second spool.

5. A device as defined in claim 3 including a stationary rotatable roller over which said unwound web travels from its spool before passing around the bottom of and supporting said dancer roll thereby forming a loop in said unwound web.

6. In a device for unwinding web from spools by the action of an unwind driving force the combination comprising a turret, a pair of rotatable spindles on said turret adapted to receive first and second spools, first and second dancer rolls on said turret, a stationary rotatable roller located adjacent said turret over which said web travels from said first spool before passing around the bottom of and supporting said first dancer roll, actuating means in association with said first dancer roll which is activatable by said first dancer roll upon the discontinuance of said supporting web, turret indexing means for rotating said turret responsive to exhaustion of the web from said first spool detected by said actuating means, means for supporting the web from said second spool above said stationary roller, and means for camming said second dancer roll away from said turret and stationary roller as the turret is indexed, the indexing movement bringing said second dancer roll down onto said web from said second spool thereby forcing it down on the top of said stationary roller but beneath and supporting said second dancer roll.

7. In a device for unwinding web from spools by the action of an unwind driving force the combination comprising (1) a turret, (2) a pair of rotatable spindles on said turret adapted to receive first and second spools, (3) a dancer roll supportable by the web being unwound from said first spool, (4) actuating means in association with said dancer roll which is activated by said dancer roll upon the discontinuance of said supporting web, (5) means for temporarily stopping the movement of said web, (6) means for severing the trailing edge of the web unwound from said first spool, (7) turret indexing means for rotating said turret thereby moving said second spool into position for being unwound, and (8) splicing means for splicing said trailing end of said web unwound from said first spool to the leading end of the web to be unwound from said second spool, said means (5), (6), (7) and (8) being activatable by said actuating means (4).
